UNITED STATES PATENT OFFICE

MARKING GARMENTS FOR IDENTIFICATION

Richard C. Baumbach, Cincinnati, Ohio, assignor
of one-half to Irvin Frey, Cincinnati, Ohio

Application August 13, 1947, Serial No. 768,370

3 Claims. (Cl. 40—2)

1

My invention relates to marking garments for identification prior to dry cleaning or laundering and involves the use of a novel device, together with a new method of application of an identification tag to garments to be dry cleaned or laundered.

Practically all dry cleaning establishments have button sewing machines and my invention, which involves the attachment of an identification tag by means of a button sewed to the garment against the tag will thus be adapted for use with the equipment ordinarily carried by the dry cleaner without the necessity of purchasing any additional equipment.

It is the object of my invention to provide a method of attaching an identification tag to a garment by means of a button which is particularly constructed to facilitate removal of the identification tag.

It is an object of my invention to provide a button for attaching an identification tag which will absorb all strains on the fabric and avoid danger of the tag tearing off or tearing the garment itself.

A further object is the provision of a type of button which may be made of various colors of fibre or plastic and which may thus be employed for additional marks or even used in advertising the dry cleaning services.

Since my preferred type of button is a flat disc it may be made very inexpensively.

A particular object is the provision of a button which may be easily removed from the garment without likelihood of tearing the fabric.

It is my object to provide a button which will not break like an ordinary button but which may be applied with either face against the identification tag so that no extra labor is involved in feeding buttons to the button sewing machine.

The foregoing objects and other advantages which will be further explained, I accomplish by the use of devices of which preferred embodiments are shown in the drawing, these devices being used in a novel method which will be outlined.

Referring to the drawings:

Figure 1 is a plan view of a preferred type of button.

Figure 2 is a side elevation of the button shown in Figure 1.

Figure 3 is an enlarged sectional view along the lines 3—3 in Figure 1.

Figure 4 is a perspective view of the button on a slightly enlarged size.

2

Figure 5 shows a button stitched in place holding an identification tag to a garment.

Figure 6 is a sectional view along the lines 6—6 of Figure 5.

Figure 7 shows how the button and tag may be removed without danger.

The button 1 is a flat, perfectly round disc having thread apertures 2 spaced so as to fit the ordinary button sewing machine. Extending between the thread apertures 2 there is slot 3 extending through the disc. It will be obvious that the button may be applied with either side against the identification tag. The thickness of the disc should be not less than one-sixteenth inches to provide an adequate reinforcement not likely to break in half.

In Figures 5 and 6 the garment fabric is indicated at 4, the identification tag at 5 and the button 1 with the stitching thread 6 passing through the apertures and extending across the slot 3.

In Figure 7 there is illustrated the manner in which the tip of a knife 7 may be inserted within the slot to cut the thread with which the identification tag is secured to the garment.

Where identification tags are stitched directly to the garment cutting the thread is likely to cut the garment. Pulling the tag off is likely to tear the garment. Where the tags are stapled with metal staples there is always danger of the staples tearing the garment. With my new arrangement the attachment of the tag is obviously so secure that no one would think of trying to pull the tag off. The use of the tip of a knife or scissors to cut the tag off is thus rendered a complete necessity in accordance with my arrangement.

Modifications in size and shape will readily occur to those skilled in the art without departing from the principle of my invention. If a wire staple is used instead of thread to hold the button in place, the slot 3 will serve as a guide for a sharp instrument with which the staple may be withdrawn.

Of course if a very weak thread is used to stitch the button to the garment, a sharp jerk on the button will break the thread, but such construction is not as satisfactory as where regular button stitching thread is used and the use of a sharp instrument to cut the thread is necessitated.

Having thus described my invention, what I claim as new and desire to secure by Letters Patent is:

1. In combination with an identification tag for attachment to a garment, a button stitched

to the garment outside the tag, reinforcing and securing said tag in position on said garment, and said button having a slot extending across at a substantial angle to the line along which the stitching extends, said slot having dimensions adapted to guide a cutting instrument to cut the stitching.

2. The combination claimed in claim 1 where-
in said stitching comprises thread.

3. The combination claimed in claim 1 where-
in said stitching comprises a wire staple.

RICHARD C. BAUMBACH.
